UNITED STATES PATENT OFFICE.

FANNIE MITCHEN DELAIIH, OF CHICAGO, ILLINOIS.

OVEN RACK.

Application filed October 20, 1927. Serial No. 227 584.

The invention aims to provide a new and improved oven rack adapted for use within an oven such as the lowermost oven of my U. S. Patent No. 976,252, said rack being provided with a grate and with novel means for adjusting this grate vertically to support the food in the oven according to the heat required for proper cooking.

With the foregoing in view, the invention resides in the novel subject matter hereinafter described and claimed, the description being supplemented by the accompanying drawing.

Fig. 1 is a top plan view partly broken away showing an oven rack constructed in accordance with my invention.

Fig. 2 is a front elevation.

Fig. 3 is a vertical transverse sectional view on line 3—3 of Fig. 2.

Fig. 4 is a horizontal sectional view on line 4—4 of Figs. 2 and 3, portions of the grate being broken away.

Fig. 5 is a vertical longitudinal sectional view on line 5—5 of Fig. 1.

Fig. 6 is an end elevation showing the grate and its supporting brackets in a different position from that shown in the other views.

The drawing above briefly described, illustrates one manner of carrying the invention into effect and while the details therein disclosed will be herein specifically described, it is to be understood that within the scope of the invention as claimed, variations may be made.

The numerals 7 and 8 denote upper and lower rectangular frames formed of L-iron or the like, and connected at their corners by vertical corner bars 9 which are also preferably of L-iron. The ends of the frames 7 and 8 are also connected by crossed braces 10 and similar braces 11 connect the rear portions of said frame.

Vertical plates 12 are secured to the crossed braces 10 and project upwardly from their crossing points, and the outwardly directed upper ends 13 of two vertical, track-forming rods 14 are secured to these plates in any desired manner, for instance by passing said ends through openings in said plates and providing them with nuts 15. The rods 14 are disposed at the inner sides of the plates 12 and the braces 10 and the lower ends of said rods may be secured at the ends of the lower frame 8, in any desired manner. In the present showing, metal strips 16 are secured to the end bars of the frame 8 and project inward-

ly therefrom, said strips being formed with openings receiving the lower ends of the rods 14, nuts 17 being threaded on said ends.

Two bracket-forming frames 18 are disposed in vertical planes at the inner sides of the braces 10, each frame having an upper portion 19 and a lower portion 20, each formed with an opening 21 through which the rod 14 passes, mounting the bracket-forming frames 18 for vertical sliding along the two rods 14. While the frames 18 may be of any desired shape, at least the upper portions 19 thereof are preferably horizontal to support a grate 22 in a manner which will prevent tilting of the latter. These frames 18 are each provided with a forwardly projecting arm 23, these arms being instrumental in raising and lowering said frames and the grate 22, and to hold the arms and consequently the parts 18—22 in any desired vertically adjusted position, I provide vertical bars 24 which preferably extend between the upper and lower frames 7—8, said bars having teeth 25 at their inner edges, with any of which the arms 23 may be engaged.

The front ends of the arms 23 are by preference formed with sockets 26 to receive appropriate operating handles such as that shown in dotted lines in Fig. 6. By engaging these handles with the arms 23 and swinging the latter inwardly out of engagement with the teeth 25, the brackets 18 may be raised or lowered as the case may demand, after which said arms may be reengaged with the teeth, thus effectively supporting the parts 18 with the grate 22 at the desired position.

A rack constructed as herein shown and described may be readily inserted in any oven to provide means for adjustably supporting a grate therein and when desired may be removed therefrom. To facilitate this insertion and removal of the rack, the same may be provided with suitable supporting rollers as shown.

While the details herein disclosed may be considered as preferred, attention is again invited to the fact that within the scope of the invention as claimed, variations may be made.

I claim:

1. In an oven rack, a vertical stationary track, a grate supporting bracket engaged with said track for vertical sliding thereon, said bracket having a projecting arm by means of which it may be raised and lowered,

and means co-operable with said arm for supporting said bracket at different positions along the length of the track.

2. In an oven rack, a vertical stationary track, a grate supporting bracket engaged with said track for vertical sliding thereon, said bracket having a projecting arm by means of which it may be raised and lowered, and a stationary vertical bar having vertically spaced teeth with which said arm is engageable to support said bracket at different positions along the length of the track.

3. In an oven rack, a vertical stationary rod, a grate-supporting frame disposed in a vertical plane and having upper and lower portions formed with aligned openings through which said rod passes, mounting said frame for vertical sliding on said rod, said frame having a substantially horizontal arm by means of which it may be raised and lowered, and a stationary vertical bar having vertically spaced teeth with which said arm is engageable to hold said frame at different elevations.

25 4. An oven rack comprising a rectangular top frame, a rectangular bottom frame, vertically disposed members secured to said top and bottom frames, a grate between said top and bottom frames, brackets supporting said grate, and means mounting said brackets for vertical adjustment.

5. An oven rack comprising a rectangular top frame, a rectangular bottom frame, vertically disposed corner bars connecting the corners of said frames, crossed braces connecting the ends of said frames, vertically disposed plates secured to said braces and extending above their crossing points, vertical rods disposed at the inner sides of said braces and having outwardly turned upper ends secured to said plates, the lower ends of said rods being secured at the ends of said lower frame, brackets slideable along said rods, a grate supported by said brackets, and means for holding said brackets at different elevations.

6. An oven rack comprising a rectangular top frame, a rectangular bottom frame, vertically disposed corner bars connecting the corners of said frames, crossed braces connecting the ends of said frames, vertically dis-

posed plates secured to said braces and extending above their crossing points, vertical rods disposed at the inner sides of said braces and having outwardly turned upper ends secured to said plates, the lower ends of said rods being secured at the ends of said lower frame, brackets slideable along said rods and provided with forwardly projecting arms by means of which they may be raised and lowered, vertical bars secured to the above-named parts and having teeth with which said arms are engageable to support the brackets at different elevations, and a grate supported by said brackets.

7. An oven rack comprising a rectangular top frame, a rectangular bottom frame, vertically disposed corner bars connecting the corners of said frames, crossed braces connecting the ends of said frames, vertically disposed plates secured to said braces and extending above their crossing points, vertical rods disposed at the inner sides of said braces and having outwardly turned upper ends secured to said plates, the lower ends of said rods being secured at the ends of said lower frame, brackets slideable along said rods, said brackets comprising open frames constructed from single flat metal strips bent to form an upper horizontal bar, a lower bar substantially parallel with and spaced from said upper bar, and end bars which incline inwardly from the upper bar to the lower bar, said lower bars being extended forwardly beyond the front of the rack to provide arms whereby the brackets may be raised and lowered, said upper and lower bars having aligned openings through which said vertical rods pass for slidably mounting the brackets thereon, vertical sockets formed in the projecting ends of said lower bars and adapted to receive handles, vertical bars secured to the front sides of said top and bottom frames of the rack, said bars having teeth with which the projecting ends of the lower bars of the brackets are engageable to support the brackets at different elevations, and a grate supported by said brackets.

In testimony whereof I have hereunto affixed my signature.

(Mrs.) FANNIE M. DELAIH.
